UNITED STATES PATENT OFFICE.

RUDOLF VON FROMMER, OF BUDAPEST, HUNGARY.

SPORTING GUN.

Application filed August 25, 1921. Serial No. 495,182.

To all whom it may concern:

Be it known that I, RUDOLF VON FROMMER, a citizen of Hungary, residing at Budapest IX. Sorokvari ut 158, in the county of Pest 5 and State of Hungary, have invented certain new and useful Improvements in Sporting Guns, of which the following is a specification.

The subject of my present invention is a 10 breech lever specially adapted for sporting guns, which is operated by an upward pressure and furnished for the barrel elongation with a bolting block, which is horizontally movable in the breech body and is connected to the breech lever by a slot and pin 15 or the like, and provided with a locking elongation. The lever is also furnished with certain arrangements, which secure it in its locked position. The present lever differs 20 from those, known already, also by being brought into its locked position by a spiral spring, arranged in a pressing organ, which is advantageously provided with a roller.

In the attached drawing the invention is 25 represented by the example of a constructional form.

Fig. 1 is a longitudinal section of the arrangement, with the breech lever in resting position.

30 Fig. 2 is the same, but with pressed back lever, with drawn back bolting block and with bent down barrel.

Fig. 3 is a cross section through the line III—III of Fig. 1.

35 Fig. 4 is a horizontal section of the breech. The lever 1 is pivoted on the pin 2 and is under the effect of the spiral spring 3, which is embedded in the pressing element 4. This

40 pressing element is pivoted on the pin 5 and communicates the effect of the spring 3 to the lever 1 by the aid of the roller 7, on the axis 6. Slidably engaged by pin 8 with the slot 9 of the lever 1 there is a bolting block 10, which is horizontally movable in the breech body and is provided with a locking elongation 11, which in the holding 45 position of the lever 1 presses upon the nose 12 of the barrel 13, locking thereby the barrel with the breech body 14. In engagement with the barrel hook, there is the well known bolt 15, which by the pin 16 is in connection with the lever 1 and is opened in the known manner by pressing back the lever 1. For fixing the lever 1 in the locking 50 position, there is arranged a slide 17,

whose track of motion is of a different direction from that of lever 1. This slide 17 is under the effect of spring 18 and in the locking position of lever 1 comes into connection with a fixed part of the gun, for instance with the trigger guard 19 by means of a notch on the same, and thus the lever 1 will be secured against an unintentional opening movement. In consequence the lever 1 can be opened, only by first pressing back the slide 17 against its spring 18 and afterwards pressing the lever 1 upwards.

What I claim as new and desire to secure by Letters Patent is as follows:

1. In combination with a breech-lever for 70 sporting guns operable by an upward pressure, a bolting block horizontally guided in the breech body and connected with the breech-lever, locking means on said bolting block adapted to lock the barrel in its 75 closed position, a spring pressed slide on the breech-lever adapted to engage in a notch on a fixed part of the gun.

2. In combination with a breech-lever for 80 sporting guns operable by an upward pressure, a bolting block horizontally guided in the breech body and connected with the breech-lever, locking means on said bolting block adapted to lock the barrel in its closed 85 position a spring pressed slide on the breech-lever adapted to snap in a notch of the trigger guard in the locking position of the breech lever.

3. In combination with a breech-lever for 90 sporting guns operable by an upward pressure, a bolting block horizontally guided in the breech body and connected with the breech-lever, locking means on said bolting block adapted to lock the barrel in its closed position, a pressing element hinged to the 95 breech body, a spiral spring on said pressing element adapted to press the breech lever into its locking position with the pressing element as intermediary.

4. In combination with a breech-lever for 100 sporting guns operable by an upward pressure, a bolting block horizontally guided in the breech body and connected with the breech-lever, locking means on said bolting block adapted to lock the barrel in its closed position, a pressing element hinged to the 105 breech body, a spiral spring on said pressing element adapted to press the breech lever into its locking position with the pressing element as intermediary, an anti-friction 110

roller on the latter to transfer the pressure of the spiral spring to the breech lever.

5. The combination with a breech-lever for guns operable by an upward pressure and adapted to actuate the ordinary bolt employed in locking the barrel, of a bolting block rectilinearly guided in the breech body,

and connected with said breech-lever, a stop lug on the bolting block, and a projection on the barrel adapted to be engaged by said stop lug for fixing the barrel in its locked position. ¹⁰

In testimony whereof I affix my signature.

RUDOLF v. FROMMER.
